PRINTING PRESS

John Duke Tyler, Birmingham, Ala.

Application September 20, 1937, Serial No. 164,726

27 Claims. (Cl. 271—4)

This invention relates to a printing press of the reciprocating bed type, that is, one in which the printing form, either of type, mimeograph stencil, plate, or other form, reciprocates beneath a cylindrical platen or impression roller, and the paper is printed by being held or pressed against the printing setup by the impression roller.

Among the special features which distinguish 10 my improved printing press are an improved sheet feeding mechanism embodying a moving belt with sheet gripping means at intervals thereon which bear downwardly on a stack of sheets by gravity. The sheets are supported in an inclined 15 position and are moved upwardly by the belt against the force of gravity, whereby gravity assists in the separation of the sheets. The feeding mechanism also embodies an improved sheet separating means which includes a frictional separating member adapted to engage each sheet, and where more than one sheet happens to be 20 engaged by the gripping means, to return the extra sheet to the stack. The separating means also embodies a frame mounting with means to 25 vary the degree of frictional engagement with the sheets being fed, whereby to adapt the feeding means to sheets of different weights and quality.

Another important feature of my invention is 30 a guide assembly consisting of lateral guides and guides to bear downwardly on the paper, also guides for directing the paper around the cylindrical platen or impression roller, all of which are coupled together and adjustable as a unit.

35 Other important features of my invention include the paper positioning means and the feeler mechanism for controlling the operation of the press responsive to paper feed. While these and other features are disclosed in this application, 40 they are to be covered and claimed in other applications.

Other distinguishing features of my improved invention will be apparent from the description and from the annexed drawings forming a part 45 of this application, in which

Fig. 1 is a plan view of my improved machine with inking mechanism removed the better to show the details of the reciprocating bed;

Fig. 2 is a side elevation drawn to a somewhat larger scale with parts broken away and with part of feeder mechanism removed;

Fig. 3 is a side elevation, partly in section, of sheet feeding means;

Figs. 4 and 5 are detail views of idler pulleys 55 employed with the feed belt;

Fig. 6 is a detail view, partly in section, of the lower, or pickup end of the feed belt with sheet separating means in place;

Fig. 7 is a detail view of the separating member and its frame removed from the feeder assembly;

Fig. 8 is a sectional view taken along the line VIII—VIII of Fig. 6;

Figs. 9 and 10 are detail views showing alternate forms of sheet gripping means;

Fig. 11 is a detail plan view of guides associated with my improved feeder mechanism and their adjusting means;

Fig. 12 is a side elevation of the guides shown in Fig. 11;

Fig. 13 is a detail view showing means included in the guide means to cause long sheets to overlap as they are fed to the press;

Fig. 14 is a detail sectional view showing delivery of a sheet of paper to the cylindrical platen;

Fig. 15 is a detail view showing the support for the end bearing of the feed roll associated with the cylindrical platen;

Fig. 16 is a fragmentary detail side elevation showing guide means which carry the sheets around the cylindrical platen, together with my improved sheet stop means;

Fig. 17 is a view taken along the line XVII—XVII of Fig. 16;

Figs. 18 and 19 show modified forms of the guides shown in Figs. 16 and 17;

Figs. 20 and 21 are detail plan and sectional views of a guide interposed between the delivery end of the feed belt and the cylindrical platen;

Fig. 22 is a fragmentary side elevation with covering wall removed showing the operating mechanism for the platen or impression roll;

Figs. 23 and 24 are plan and elevational views respectively of the platen or impression roll and its frame;

Fig. 25 is a transverse sectional view taken along the line XXV—XXV of Fig. 22;

Fig. 26 is a perspective view of the feeler mechanism employed with my improved printing press;

Fig. 27 is a perspective view of rocker arm and segmental gear of feeler mechanism;

Figs. 28 to 32 inclusive are detail sectional views showing the cycle of movement of the feeler element;

Fig. 33 is a detail view of rocker arm and segmental gear of feeler mechanism taken on opposite side from Fig. 27;

Figs. 34 and 35 are detail perspective views

Illustrating in part the controlling action of the feeler mechanism;

Fig. 36 is a sectional view taken along the line XXXVI—XXXVI of Fig. 35;

Fig. 37 is a sectional view of the switch operating mechanism; and

Fig. 38 is a view looking in the direction of the arrows XXXVIII—XXXVIII of Fig. 37.

The machine is supported on suitable leg or frame supports 10, on which is mounted a driving motor 11. If desired, it may also be driven manually by the crank C at the side, shown in Fig. 1. The motor drives the press through a belt 12 and a train of gears 13. The moving parts of the press are located in a cabinet frame 14 of box-like construction. Driven from the train of gears 13 is a sprocket wheel 16, over which runs a sprocket chain 17, and which passes over a second sprocket wheel 18 mounted in the cabinet frame. Carried by the sprocket chain 17 is a pin 19, which bears in a yoke 21 carried by a reciprocating bed 22. The bed 22 rests upon rollers 23 riding on a suitable track 5 in the side of the frame 14. When the machine is in operation, each time the bed 22 reciprocates, an impression roller or platen 24 mounted above the bed 22, presses a sheet of paper against a printing form on the bed in a manner well understood. Rotating with the sprocket 16 is a worm 15 which meshes with a gear 20 and drives the latter in synchronism with the sprocket. A link 25 connects the gear 20 to the arm of a hydraulic snubber 30. The relation of the gears is such that the gear 20 rotates twice for each reciprocation of the bed 22, whereby the snubber acts as a shock absorber at each end of the stroke of the bed.

Driven from the train of gears 13 is a gear 26 mounted on a shaft 27, which extends through the side wall of the frame of the machine and through gears 28a drives a shaft 28 mounted in bearings 29 on the side of the frame. The other end of the shaft 28 has a miter gear 31 meshing with a similar gear carried by a shaft 32 extending across the frame of the machine, and carrying on its opposite end a miter gear 33 through which a longitudinally extending shaft 34 is driven. The shaft 34 drives a cross shaft 36 through bevel gears 37, which cross shaft is the main drive for a feed belt 38.

The feed belt 38 is made of fabric, rubber, or other suitable flexible material, and is formed with transverse segmental projections 39 on its inner surface which mesh with segmental grooves 41 formed on a driving sprocket 42 carried on the shaft 36. The drive sprocket 42 is driven from the shaft 36 through a manually operable clutch 300 which is preferably designed to yield and slip in event there should be too heavy a load on the feed belt such as might occur should a sheet become rumped or tangled in its way through the machine. By disengaging the clutch manually the machine may be run without the paper feed, which is desirable in starting up, permitting a thorough inking of the printing form. The position of the drive sprocket 42 on the shaft 36 may be adjusted laterally, as by means of set screws 35. This adjustment is important in that the belt must be properly aligned or else the paper will move laterally from its proper direction.

An idler 43 bears on the upper surface of the belt 38 and bends it around the sprocket 42 to cause a maximum number of transverse segments to mesh with the teeth in the driving sprocket. The rearward end of the feed belt 38 runs on an

idler pulley 44 carried by a shaft 46 extending across the bed of the machine. The position of the pulley 44 on the shaft 46 may be adjusted as by means of adjusting screws 45. (See Fig. 14.) The forward end of the feed belt 38 turns downwardly from the drive sprocket 42 and passes over an idler pulley 47 carried by a yoke 48, which yoke is pivotally mounted at 49, whereby it is free to swing around its pivot point 49 to adapt itself with its assembly to the stack of paper from which the belt is feeding. The yoke 48 is provided at its lower end with a slot 51 in which the journals 52 of the idler 47 are mounted, whereby it is free to move in the slots to accommodate itself to the position of the belt 38.

The paper to be fed to the machine is carried in a rack 53 inclined downwardly at an angle of approximately 60° from the frame of the machine whereby to take advantage of the force of gravity in the separation of sheets, as will hereafter be shown. The lower end of the rack 53 is provided with an adjustable bracket 54 to accommodate sheets of different lengths, and is so adjusted as to bring the upper ends of the sheets directly beneath the idler pulley 47. The idler pulley 47 is mounted on the shaft 52 separately from disks 56 and 57 at each end thereof, which disks are larger in diameter than the pulley 47 and which bear against the pile of sheets of paper to be fed to the machine (Fig. 4). The purpose of this is to provide a gap between the paper and the pulley 47 under which the paper passes and to insure that there will be no frictional pull by the belt on the sheets until it is the proper time for a sheet to be fed to the machine, as will presently be described. As an additional precaution, thin disks 58 and 59 are provided between the ends of the pulley 47 and the disks 56 and 57 to insure against frictional rotation of the disks 56 and 57 by reason of lateral engagement with the feed belt 38.

The feed belt 38 preferably carries on its outer surface at regular intervals, gripping means such as friction pads 61 to engage paper in the rack 53 and feed it to the printing machine. Instead of the pads 61 depending entirely upon friction, they may be made of soft rubber with vacuum cups 60 formed therein at intervals, as shown in Fig. 10. The friction pads 61 are preferably made of sponge rubber, or some substance having a similar gripping property with respect to paper. As shown in Fig. 9, the friction pads 61 are narrow pads mounted upon metal strips 62, which fit in guides 63 permanently mounted on the outer surface of the belt 38, whereby the number of the pads may be varied to suit paper of different weights and lengths, and also the pads may be renewed in case they become worn. The pads 61 are shorter than the width of the belt, as seen in Fig. 5, whereby the belt may run over the disks at the ends of pulley 47 without the pads bearing against the disks or the pulley.

Carried by the adjustable bracket 54 (Figs. 1 and 3) is a short plate or step 64, upon which the lower end of a pile of sheets of paper rests. Also at the upper end, beneath the lower end of the feed belt 38, there is provided an inclined guide member 66 which, in cooperation with the plate 64, causes the sheets to be bowed, or to sag in the center, whereby when the top sheet is pulled by the feed belt 38, it is straightened and thus lifted clear of the stack at the center as shown in Fig. 3, which aids in the separation of the sheets by reducing the sliding friction between them.

The means for separating the sheets so that only one sheet at a time is fed to the machine will now be described with reference to Figs. 3, 6 and 7. Pivotedly mounted at 87 on the rack 53 is an arm 68 which extends downwardly along the rack 53, the lower end thereof being a short distance above the idler roller 47 and just above the guide member 69. The extreme lower end is formed as curved guides 69 which are on each side of the feed belt 38, and which bear against idler disks 11 carried on a shaft 72 mounted in the yoke 48, as best seen in Fig. 8. Attached to the lower end of the arm 68 by means of a hinge 73 is a yoke member 74. A compression spring 76, adjustable by usual knob and screw threaded means, serves to press the yoke member 74 toward the lower end of the arm 68. In the lower end of the yoke member 74 is mounted a shaft 77 which carries a semi-cylindrical soft rubber separating member 78. The separating member 78 is normally held in the position shown in Fig. 7 of the drawings, by means of a torsion spring 79, which has one end engaged by the separating member 78 and the other in the bearing at the end of the shaft. The separating member 78 thus resists turning in a clockwise direction, as seen in the drawings.

Connected to the arm 68 is a fork 81, to which is connected a chain 82 which passes over a pulley 83 attached to the rack 53. The other end of the chain 82 is connected to an adjustable collar 84 mounted on a rod 86 pivotally connected at 87 to the rack 53. Also mounted on the rod 86 is a weight 88, which may be adjusted in its position on the rod whereby to vary the force of the chain 82 pulling against the fork 81. The arrangement just described serves to force the separator assembly upwardly toward the feed belt 38, so that the guides 69 bear against the idler disk 11 at all times, regardless of the level of the paper in the rack. A counterweight roller 89 is carried by a yoke 91 which is pivotally mounted at 92 on the yoke assembly 48.

With the feed belt 38 driven in the direction shown by the arrows, the friction pads 61 come in contact with the top sheet of a pile of sheets in the rack 53, due to the fact that they extend beyond the plane of the disks 56 and 57 and the top sheet, and possibly other sheets, are pulled upwardly by the friction pads. When the sheet reaches the separating member 78, it is engaged thereby, and if more than one sheet is being moved, the separating member will detach the lower sheet so that only a single sheet is carried upwardly along the rack. As the sheet or sheets of paper are drawn upwardly over the separating member 78, it is turned around its shaft against the action of the spring 79 until its lower edge is bearing against the sheet of paper above it, whereby the force and effect of the semi-cylindrical separating member is concentrated on a smaller area, and the effect of the torsion spring is to force the sheet backwardly. Thus if there be two sheets over the separating member, the lower sheet will not only be separated from the other, but will be forced backward on to the stack of sheets. Tightening the adjustment of the spring 76 increases the frictional engagement of the separating member 78 with the sheets of paper, while loosening the adjustment decreases the frictional engagement. By this means, and by means of the counterweight 88, the separating mechanism can be adjusted so as to accommodate itself to any class

or weight of paper being handled by the feeder. The torsion of the spring 79 may also be varied by changing the position of the shaft 77 by means of the kerf 83 provided in the end thereof, the shaft 77 being frictionally held in place 5 will remain in any position it may be placed.

As the paper is carried upwardly, after being separated, it is engaged at the upper end of the rack 53 by means of a power driven soft rubber roller 94, which aids the feed belt 38 in delivering the sheet of paper on to the flat plate 96 forming the upper surface of the printing machine.

The paper in its travel toward the cylindrical platen 24 is guided by lateral guides 97 mounted 15 on the bracket 53, and lateral guides 98 mounted on the flat top of the frame 14. These guides are all adjusted simultaneously by means of threaded shafts 99 and the shaft 46 which is also threaded. These shafts (see Figs. 11 to 13), 20 extend through in threaded engagement with the guides and have right hand threads on one end thereof and left hand threads on the other, and are connected by means of a shaft 101 through miter gears 102 and a universal coupling 103. A hand wheel 104 attached to one of the shafts serves to turn them all simultaneously through the media of the gears just described.

Detachably mounted on the lateral guides 98 30 by means of clips 95 are guides which lie above the moving sheets along their side edges. At 100 is shown a short resilient guide, which brings about an overlapping of the ends of the sheets when long sheets are being fed to the machine. 35

Each sheet of paper is carried forwardly on the top 96 of the machine by means of the friction pads 61, toward the cylindrical platen 24. For the major portion of the distance between the rear edge of the top 96 and the idler pulley 44, the belt bends downwards by gravity, so that the pads 61 are in engagement with the sheet. The idler pulley 44 is elevated sufficiently above the top 96 that the belt and pads would clear a sheet of paper beneath them. Beneath the idler 45 pulley 44 and extending slightly forwardly of it is a resilient metal strip 106 over which each sheet is drawn, the object of which is to press the paper upwardly against the friction pads 61 and to insure a firm frictional engagement during the last portion of the travel of the paper. A movable wedge 107 is interposed beneath the plate 106 whereby the position at which the positive grip of the paper is broken may be varied. This adjustment permits sheets of different 55 weights and kinds to be delivered against fixed position stops beyond the feed belt.

The forward end of the sheet of paper S passes under a guide 108 (Fig. 14) and between upper guide 109 and lower guide 111 over a 60 frictionally driven feed roller 112, and thence into a wedge shaped pocket 113 formed between small rollers 114 and the cylindrical platen 24, when the cylindrical platen is in its raised or upper position. The small roller 114 is carried by an oscillatory arm 116 pivotally mounted at 117 on a curved guide 118. (See Figs. 16 and 17.) The curved guides 118 (one on each side) are mounted on the ends of the lateral guides 98 whereby to be adjustable therewith. A spring 70 119 serves to cause the roller 114 to bear against the cylindrical platen 24 at all times.

The guide 108, shown in detail in Figs. 14, 20 and 21, comprises a hook 105 which is hooked over the shaft 132, and a lower bifurcated por- 75

tion 110 which extends forwardly and serves to hold the sheet of paper down on the top 98. The feeler element, to be described later, is disposed between the arms 110. Fingers 115 attached to the arms 110 hook over the feeler shaft 161 and serve to prevent the guide from exerting too much downwardly pressure on the sheet. Pivotedly connected to the forward end and beneath the guide 108 is a member 120 under which the sheet S passes, and which carries a soft rubber or similar friction tip 125 which bears downwardly on the sheet. When the sheet S has been brought to a stop by the rollers 114, the friction tip 125 resists backward movement of the sheet and holds it in place.

In Figs. 18 and 19 I show a modified form of curved guides adapted for cooperation with the cylindrical platen 24. In accordance with this modification, I provide on the side of the guide 20 118 a curved arm 318 which carries a plurality of rollers 314. The curved arm 318 is pressed by a torsion spring 319 in the direction to maintain the rollers 314 in contact with the cylindrical platen 24 in all positions thereof. The forward roller 314 in cooperation with the cylindrical platen acts as a stop member for the forward end of the sheet, as already described. With this form of guide, a better grip upon heavy sheets of paper is provided, and there is less danger of clogging of the press by failure of the platen to pull the sheets around.

The position of the friction pads 61 on the belt 38 is such, and the movement of the belt is so synchronized with the movement of the bed 35 22, that when the sheet of paper S reaches the point just described with its forward edge stopped by the roller 114, the friction pads 61 no longer engage the sheet, but the belt is so disposed with respect to the top 98 that there is a slight brushing contact of the belt against the rear end of the sheet which is just enough to hold the paper against the roller 114 until the time comes for it to be carried further on and printed.

The wedge shaped pocket 113, formed in the manner just described, comprises an extremely accurate stop for the forward ends of the sheets of paper so that there is exact registry of printing matter whenever a sheet has been run through the machine more than once. It is understood that the paper assumes the position described when the cylindrical platen 24 is in its upper position, and that the upper position of the cylindrical platen is the same every time it is raised.

When the cylindrical platen is lowered, it bears against the sheet of paper resting on the feed roller 112, and its end bear against the side rails of the bed 22 so that it is rotated by frictional engagement therewith. As it is rotated counter-clockwise, the paper is gripped firmly between the cylindrical platen and the feed roller 112 and the small roller 114 and is guided by the curved guides 118 around the cylindrical platen, from whence it is delivered over a delivery roller 121 driven by a belt 122 from a shaft 132. Additional gripping of the paper in its travel around the cylindrical platen 24 is provided by fixed rollers 118a in the curved guides 118. An additional guide 320, disposed midway the ends 70 of the platen, aids in guiding the sheet around the platen. Bearing downwardly on the delivery roller 121 at each side thereof is a ball 124 which is free to rotate in a sleeve 126 so that the sheet of paper is gripped between the delivery roller 121 and the ball 124. The delivery roller 121

has a surface speed faster than the surface speed of the cylindrical platen 24, so that there is a slippage between the delivery roller and the paper so long as it is under control of the cylindrical platen 24. As soon as the paper passes from between the cylindrical platen to the feed roller 112 and small roller 114, it is quickly carried away by the delivery roller 121 and delivered on to a laterally moving wide belt 127, and from thence it passes to a receiving rack 128 on the side of the machine. (See Fig. 1.) On leaving the belt 127 each sheet passes beneath an idler roller 129, and over a rubber roller 127a driven by a belt 133 from the shaft 24, which provides a positive discharge of each sheet into the receiving rack.

The static electricity collected by the paper in its passage through the machine causes it to be attracted toward the metal of the frame of the machine. Unless some provision is made to overcome the effects of this attraction, the sheets of paper would become blocked in their delivery. By passing them underneath the idler roller 129 over the power driven roller 127a, the paper is pulled away from the delivery belt 25 and into the delivery rack before it is turned loose. When the paper is delivered from the delivery roller 121 on to the wide belt 127, it is stopped on its rearward travel by a pair of rotary disks 134 mounted on a plate 138, the position of which may be adjusted to accommodate different length sheets. The disks 134 rest upon the wide belt 127 and rotate therewith.

As the reciprocating bed 22 moves forward and backward, the printing form thereon is supplied with ink from an ink roller assembly 137. When the bed is completing its rearward movement, the cylindrical platen 24 is lowered. When there is paper beneath the cylindrical platen 24, it is pressed against the printing setup and is held there against during the forward movement of the bed 22. When there is no paper beneath the cylindrical platen 24, it is immediately raised as the bed 22 moves forward, by mechanism to be described presently, and the circuit to the motor 11 is broken automatically so as to stop the machine.

The cylindrical platen is mounted on a shaft 138 extending therethrough and protruding at the ends thereof to fit into vertical slots 139 formed in end members 141 (Figs. 23, 24). The vertical position of the cylindrical platen in the slots 139 is determined by the position of cams 142, one at each end of the cylindrical platen and having curved slots 140 through the ends of the shaft 138 extend. Bearing against each of the cams 142, at the top thereof, is a plate 143 carried by a cross member 144, which is normally pushed downwardly by a spring 146 bearing at its upper end against a cross member 147 which connects the two plates 143. Carried by each of the plates 143 is a guide member 340, which fits in its associated slot 139 above the shaft 138 of the platen 24. As shown in Figs. 2 and 22 of the drawings, the cam 142 has just raised the cylindrical platen 24 to its highest position and the bed 22 is in its extreme right-hand position. In that position, it will be noted that a lug 148 carried by the bed 22 has struck the lower end 149 of the cam and moved it to the position shown. In this position, the upper surface of the cylindrical platen 24 at each end thereof is engaged by a brake shoe 151 having a stem 150 which extends upwardly through the cross members 144 and 147 and which is pressed 75

downwardly against the roller 24 by a spring 152 so as to prevent rotation thereof when in its upper idle position.

When the cylindrical platen is down in printing position, the ends bear against the side rails 155 and the platen is rotated by friction with the side rails and with the printing form. As will be seen in Fig. 2, the side rails at their ends are provided with depressions 160, so that as 10 the bed reaches the end of its stroke, the cylindrical platen is supported clear of the side rails by the lower sides of the slots 140 and the cylindrical platen ceases to rotate and when again engaged by the side rails starts from a dead 15 stop.

Extending across beneath the rear side of the cylindrical platen 24 is a feed roller 112 which is mounted in ball bearings 153 in the side frame of the machine. (See Figs. 15 and 22.) A leaf 20 spring 154 serves to push the bearings upwardly, but not to a sufficient distance for the feed roller 112 to contact with the cylindrical platen 24 when the latter is in its upper position, but sufficiently so that the spring 154 is flexed and 25 the feed roller is held yieldingly against the cylindrical platen when the latter is in its down-most position, so as to hold the paper there-against when the machine is printing.

When the cams 142 are thrown either to the 30 position to hold the cylindrical platen 24 in its uppermost position or in its lowermost position, they are yieldingly held in that position by means of balls 165 (Fig. 24) bearing in sockets 156 in the cams (Fig. 22).

35 The operation of the cylindrical platen and of the machine itself is controlled by a feeler mechanism, which will now be described.

Pivoted on the side of the frame of the machine is a rocking member 157 carrying a 40 segment 158 of a gear on its upper end which meshes with a gear 159 mounted on the shaft 161 which extends across the frame of the machine ahead of the cylindrical platen. Mounted near each end of the shaft 161 is an eccentric 162 45 which is adapted to turn in a yoke 163 to cause the yokes to reciprocate in vertical guides 164 in the side wall of the machine. Journalled on the lower end of each yoke is a roller 166.

The shaft 161 has mounted on its other end a 50 torsion spring 167, which tends constantly to rotate the shaft counter-clockwise, as seen in Figs. 26 and 28 to 32 inclusive of the drawings. The shaft 161 is loosely connected to the gear 159 by means of a pin 168 which is fixed to the 55 shaft and bears against a segmental boss 169 on the gear. By means of this connection the gear may turn the major portion of a complete revolution without turning the shaft 161.

The feeler mechanism on the shaft 161 consists in an elongated curved plate member 171 60 pivoted on a small bracket 172 to the shaft 161. On the forward edge of the member 171, as seen in Figs. 26 and 28, there is a small rubber tip 173 which is non-rotatable. The curved member 65 171 is normally held in the position shown in Figs. 28, 29 and 30 of the drawings relatively to shaft 161, by a tension spring 174, which normally holds the forward edge of the member 171 against the shaft. The member 173 is thus normally held in the position shown with respect to the shaft 161, so that when it assumes the position shown in Fig. 29 it has engaged an idler roller 176 mounted in the flat plate 96 of the machine and can turn no further due to the fact 70 that the center of the feeler tip is to the rear 75

of a line drawn through the center of its pivot point and the center of the idler roller 176, and the forward edge of the member 171 is against the shaft 161. Should there be a sheet of paper S being fed to the machine, between the tip 173 5 and the roller 176, when that sheet of paper is pulled forwardly by the action of the cylindrical platen 24, as seen in Fig. 31, it raises the tip 173 over the roller 176, and the spring 167 then rotates the shaft 161 to the position shown in 10 Fig. 32 of the drawings. This causes a rotation of the eccentrics 162 sufficiently to bring the yokes 163 and their rollers 166 to their lowest position.

Mounted on the forward end of the bed 22 in 15 brackets 178 and 179 is a rocker shaft 181 having a hook 182 at one end thereof. The rocker shaft 181 is biased by a spring 183 to draw the hook in the direction shown by the arrow in Fig. 26. The hook 182 is positioned to engage a roller 20 184 mounted on the lower end of the rocker member 167, when the bed 22 approaches the end of its forward travel. The member 167 is constrained to rock in the opposite direction by a spring 186 connected below the pivot point of 25 the rocker member and to the frame of the machine. When the bed 22 is at the extreme end of its forward travel, which is the position shown in Figs. 22 and 26, of the drawings, the upper end of the member 157 with its gear 158 has been 30 moved to its extreme left hand position, as shown in the drawing by the engagement of the hook 182 with the roller 184. This movement has rotated the gear 159 clockwise, and the segment 35 169, coming against the pin 168, has rotated the shaft 161 in a clockwise direction to raise the rubber feeler tip 173 to its upper position so that the sheet of paper may pass freely beneath it. This movement rotates the eccentrics 162 in their 40 yokes 163 to raise the yokes to the uppermost position. In this position, a shoulder 187 on the right hand yoke has been engaged by a hook 188 which is carried by member 189 pivoted at 191 to the frame of the machine. Mounted on the upper end of the member 189 is a roller 192 45 which engages one of the plate members 143, which latter move up and down with the cylindrical platen 24. Provided in one edge of the plate member 143 is a depression or cam surface 193 which the roller 192 is adapted to enter when 50 the cylindrical platen is in its upmost position, permitting the hook 188 to engage the lug 187 and hold the feeler mechanism in the position shown in Fig. 26 of the drawings. When the cylindrical platen 24 later moves to its lowest 55 position, the plate 143 moves downward and the roller 192 is moved out of the slot 193 to disengage hook 188 from the lug 187, allowing the shaft 161 with its feeler mechanism to rotate counter-clockwise to engage the paper if present, or the roller 176 if no paper is present, as already 60 described.

When the reciprocating bed 22 starts to move rearwardly, or to the left as shown in Figs. 22 and 26 of the drawing, the hook 182 releases the roller 184 and the spring 186 pulls the lower end of the member 157 to the left so that the member 157 assumes the position shown in Fig. 27 of the drawings. In that position, the lug 169 has moved around to the opposite side of the pin 70 168 carried by the shaft 161, leaving the shaft 161 free to rotate under the influence of the spring 167, as already described.

As before pointed out, when the reciprocating bed 22 has reached its extreme right hand posi- 75

tion, a lug 148 on the bed engages the lower end 149 of the cam 142, raising the cylindrical platen 24 to its upper position. In this position, the roller 162 is in the depression 163 and the frame 5 163 for the eccentric 162 is engaged by the hook 168 to hold it in its upper position with the feeler 173 rotated clockwise to its extreme position to receive paper, as seen in Figs. 27 and 28.

The cylindrical platen 24 remains in its upper 10 most position during the travel of the reciprocating bed 22 rearwardly. Just before the bed 22 reaches its extreme rearward position, a lug 164 carried by the bed 22 engages the lower end 149 of the cam 142, moving it to its other position to lower the cylindrical platen 24. (See Figs. 34 and 35.) When it is moved to its lower position, the plate 143 is lowered and the roller 162 moves out of the depression 163 to release the hook 168, permitting the shaft 161 to be rotated 20 by the spring 167 to institute the feeler action already described.

The control of the cylindrical platen from the feeler mechanism will now be described.

Mounted on the side of the reciprocating bed 25 22 (Figs. 34 and 35), near the rearward end thereof, is a member 198 which is pivoted at 197 and held in place by a screw 198 in a slot 199, which permits some longitudinal adjustment of the member (see Fig. 2). The member 198 is constrained in its pivotal movement by a screw 201. A spring 202 behind the member 198 serves to thrust it outwardly as far as the screw 201 will permit (see Fig. 36). At the rearward end of the member 198 is a roller 203 which, when the member 198 is in its outermost position with respect to the bed 22, lies in the path of the lower end 149 of the cam 142, so that under such conditions it will strike the lower end of the cam and raise the cylindrical platen as the bed moves to the right, as seen in Figs. 34 and 35 of the drawings.

Slightly forwardly of the roller 203 on the member 198 is a lug 204 having a rounded nose 206. When the bed 22 has moved to a position 45 to begin the printing stroke, and the cylindrical platen has been lowered by reason of the engagement of the cam 149 with the lug 194, and there is a sheet of paper beneath the cylindrical platen 24 to be pulled through beneath the feeler tip 173 so that the shaft 161 is rotated to the left, the roller 166 on the lower end of the eccentric yoke 163 moves downwardly to its lowest position, as seen in Fig. 34, and engages the rounded nose 206 of the member 204, causing it to be pushed inwardly of the bed as the bed moves forwardly, thus moving the roller 203 out of the path of the cam arm 149, and permitting the cylindrical platen 24 to remain in its lowest position, where it is rotated by contact with the side rails of the bed, pulling the sheet of paper through and in contact with the printing form on the reciprocating bed 22.

Should there be no sheet of paper beneath the cylindrical platen 24, the feeler mechanism 65 will not be actuated by reason of the fact that the feeler tip 173 is prevented from passing the roller 166, as already described, as the bed moves rearwardly, and the roller 166 will remain in a position above the lug 204, so that the roller 203 under such circumstances engages the cam arm 149, raising the cylindrical platen 24 from the bed, and there is no engagement with the printing form.

Mounted on the side of the frame of the machine 75 is a switch 207 for controlling the motor

11, which may be operated manually by a button 208, or automatically by the movement of the bed 22 responsive to failure of paper supply through the machine. The switch 207 is actuated directly from a ratchet and pawl mechanism 209. (See Figs. 25, 35, 37 and 38.) A ratchet sleeve 211 has on its outer end a bevel gear 212 which meshes with a bevel gear 213 carried by a trip arm 214, the upper end of which has a finger 216 which extends into the path of travel of a lug 217 carried by the member 198.

When paper is being fed to the machine and the roller 166 strikes the lug 204 to hold the member 198 inwardly of the bed 22, the lug 217 passes freely past the finger 216 and the switch 15 is not actuated. Should there be a failure of the paper feed, however, the roller 166 remains in its upper position out of the path of the lug 204, as already described, and the lug 217 then strikes the finger 216 as the bed 22 moves to the right, actuating the switch 207 to shut off the motor. The shaft 218 of the switch 207 extends through the sleeve 211 to the button 208, so that, by means of the button 208, the switch may be actuated manually independently of its actuation by the arm 214.

On the opposite side of the machine there is a trip arm 218 which is similar to the trip arm 214 just described and which operates in a similar manner. The lower end of the arm 218, however, is bent round at 220 to form the hammer for a warning bell 225. Should there be a failure of paper feed the trip arm is struck by the lug 204 and the bell 225 is rung.

The arm 214 is biased to hold the finger 216 in the path of the lug 217 by a torsion spring 222 having one end secured in a small plate 223 and the other to a collar 224 secured to the arm 214. When starting the machine, it is, of course, necessary that the machine continue to operate until paper reaches the cylindrical platen 24. This is accomplished by means to hold the finger 216 out of the path of the lug 217. A pin 226 secured to the collar 224 extends into the path of a disk 227 mounted on a stem 228 and is forced inwardly of the machine by means of a spring 229. This holds the finger 216 normally in the path of the lug 217. If it be desired to withdraw the finger 216 from the path of the lug 217, a button 231 on the end of the stem 50 228 is held outwardly manually, which will permit the machine to continue to run.

Mounted on the side of the frame, above the end of the shaft 161, is a sheet counter 210 of standard commercial construction, which need 55 not be described in detail. This sheet counter is actuated from the shaft 161 through the medium of a small chain 221. When a sheet of paper passes through beneath the cylindrical platen 24 and the shaft 161 is turned to its extreme position by the spring 167 due to the sheet of paper passing beneath it, then, and only then, is the shaft moved far enough by the spring 167 to actuate the counter 210. Thus the counter is actuated only when a sheet of paper passes 60 through the machine and is printed.

From the foregoing description the operation of my improved printing press will be apparent. The sheets to be printed are placed in the rack 53 beneath the forward end of the feed belt 38. 70 Inasmuch as the yoke 48 in which the forward pulley 47 is located is pivoted at its upper end, the yoke swings by gravity around its pivot point to accommodate itself to different height of stacks of sheets. As the sheets are fed from the stack, 75

the lower end of the belt automatically follows the stack and the last sheets are as readily fed as the first.

5 The gripping means 81 on the belt engage the sheets one at a time and pull them over the separating member 18, which serves to prevent more than one sheet at a time being fed to the press.

Inasmuch as the rack 53 is naturally at an 10 angle of approximately 60°, gravity aids in the separation, as well as the fact that the ends 15 of the sheets are elevated with respect to the intermediate portion, whereby when the upper end of a sheet is gripped, it is freed between its ends. The sheets are pulled upwardly over the 20 power driven roller 94 at the top of the rack, thence along the flat top 88 to the idler pulley 46 where the belt leaves the sheets. The 25 position in which the gripping members 81 are disengaged from the sheets can be varied by varying the position of the wedge member 107 under the resilient plate 108. As a sheet is disengaged from one end of the belt, the other end reaches the pocket formed by the rollers 114 with the 30 cylindrical platen 24 and are thereby stopped. In this position, the platen is up, the feeler element 173 is in position to receive the sheet, and the stop member 125 of the guide 108 is holding the sheet against backward movement. Also the belt has a brushing contact with the sheet which 35 tends to hold it in its stopped position.

Just as the reciprocatory bed 22 is completing its non-printing stroke, with the cylindrical platen 24 raised, the lugs 194 strike the lower ends 149 of the cams 142, lowering the platen. When 40 this occurs, the yokes 163 are released and the spring 167 rotates the feeler shaft 161 so that the feeler element 173 comes in contact with the sheet over the interrupter roller 176. The bed 22, now starting on its return or printing stroke, 45 pulls the sheet S and the feeler element past the interrupter. This rotates the eccentrics 162 further so as to lower the rollers 166 into the path of the cams 204, pressing the rollers 203 out of the way of the lower end of the cams and permitting the bed 22 to complete its printing stroke 50 with the cylindrical platen 24 resting on it and rotating to draw the sheet of paper through in contact with the printing form.

Should there be a failure of paper feed, the 55 feeler movement would not be completed and the eccentrics 162 would consequently not rotate sufficiently for the rollers 166 to engage the cams 204, so that the roller 203 would strike the lower ends 149 of the cams 142, immediately raising the cylindrical platen 24 again and preventing 60 it from contacting with the printing form. Also the lug 217 would engage the finger 216, operating the switch 207, shutting off the power of the motor and ringing the warning bell 225.

65 As the sheets are printed, they are conveyed around the cylindrical platen by the guides 118 and 320, and pass between the delivery roller 121 and the balls 124, which are mounted on and carried by the upper ends of the lateral guides 98 so as to be adjustable therewith. The sheets 70 are delivered by the delivery roller 121 on to the laterally moving belt 127, from whence they pass beneath the idler roller 129 and over the power driven roller 127a to the delivery rack on the sides of the machine. It will be noted that they are delivered face up so that the operator can note imperfections promptly, if any there be.

75 My invention has proved to be extremely reliable in operation, particularly with respect to the feeding means, the sheet stops cooperating with

the cylindrical platen, and the feeler action controlling the operation of the press. The guide assembly, by means of which all of the guides are adjustable as a unit, has also proved extremely efficient, enabling the operator to set 5 the apparatus in a moment for any width of sheets. The other details of construction and operation hereinbefore described all contribute to the improved result obtained with my press.

No particular example of printing form has 10 been described in this application, as it will be apparent that the press is adapted for any of the standard types of printing form. It will also be apparent that any desired form of inking apparatus may be employed with my improved 15 press.

While I have shown my invention in but one 20 form, it will be obvious to those skilled in the art that it is not so limited, but is susceptible of various changes and modifications, without departing from the spirit thereof, and I desire, therefore, that only such limitations shall be placed thereupon as are imposed by the prior 25 art or as are specifically set forth in the appended claims.

What I claim is:

1. A sheet feeder mechanism for printing presses and the like comprising a moving belt adapted to bear by gravity on a pile of sheets, and sheet gripping means at intervals on the 30 belt to engage and move the top sheet from the pile.

2. A sheet feeder mechanism for printing presses and the like comprising means to support a pile of sheets in an inclined position, a 35 moving belt overhanging the pile and bearing against the upper end thereof by gravity, and means on the belt for engaging the top sheet and moving it upwardly off the pile.

3. A sheet feeder mechanism for printing 40 presses and the like comprising means to support a pile of sheets in an inclined position with the ends elevated relative to the center of the pile, a moving belt having one end overhanging the pile of sheets and bearing against the upper 45 end of the pile of sheets by gravity, and sheet gripping means at intervals on the belt to engage the top sheet and move it upwardly from the pile.

4. A sheet feeding device for printing presses 50 and the like comprising an inclined rack in which a stack of sheets are supported, a moving belt having one end overhanging the sheets and resting thereon by gravity, means disposed at intervals along the belt adapted to engage the top sheet and move it upwardly from the stack, and a flat bed extending from the upper end of the inclined rack in which the sheets are supported, the sheet engaging means on the belt being adapted to retain its engagement with the sheets 55 and convey each sheet along the flat bed.

5. In a sheet feeding device for printing presses and the like, the combination of a supporting rack for a stack of sheets, a conveying belt having one end overhanging the rack, an idler pulley for the lower end of the belt where it overhangs the stack, flanges on the idler pulley separating the belt from the stack, means supporting the pulley whereby the said flanges press against the stack of sheets by gravity, and means 65 at intervals along the belt adapted to engage successively the top sheets and move them one at a time from the stack.

6. In a sheet feeding device for printing presses 70 and the like, the combination of a supporting 75

- rack for a stack of sheets, a conveying belt having one end overhanging the rack, an idler pulley for the lower end of the belt where it overhangs the stack, flanges for the pulley which are freely rotatable relatively thereto and which rest upon the stack to separate the main portion of the belt from the stack, means supporting the pulley whereby the flanges thereof press against the stack of sheets by gravity, and friction means at intervals along the belt which extend from the belt through the space determined by the said flanges so as to engage the sheets and move them one at a time from the stack.
7. In a sheet feeding device for printing presses and the like, the combination of a supporting rack for a stack of sheets, a conveying belt, friction means at intervals along the belt to engage the sheets and move them one at a time from the stack, a series of guide means for the sheets extending along the rack and the remainder of the press and relatively to which the sheets are moved, and means for adjusting the position of all the guide means simultaneously to accommodate sheets of different width.
8. In a sheet feeding mechanism for printing presses and the like, the combination of an inclined rack in which the sheets are supported, means in the rack for elevating the ends of the sheets above the floor of the rack whereby the sheets assume a bowed position, a moving belt overhanging the rack, friction means at intervals on the belt adapted to engage the upper ends of the sheets and move them one at a time upwardly of the rack, the exertion of tension on the upper ends of the sheets tending to straighten said sheets whereby to separate each top sheet being fed from the sheets therebelow.
9. In a sheet feeding mechanism for printing presses and the like, the combination of a rack in which the sheets are supported, a flexible moving belt overhanging the rack, friction means on the belt to engage the sheets and move them one at a time off the rack, a separating member over which the sheets are drawn by the belt having a surface to which said belt and paper are readily conformable, said flexible belt flexing readily relatively to said separator and sheets to conform thereto whereby to increase the effectiveness of said separator.
10. In a sheet feeding device for printing presses and the like, the combination of a flexible moving belt passing over a stack of sheets, gripping means on the belt positioned to bear against the stack of sheets and to feed the sheets one at a time from the stack, a separating member adapted to engage frictionally the sheets from beneath and having a surface to which said belt and paper are readily conformable, means to vary the degree of engagement of the separating member with the sheet, and means to vary the position of the separating member to accommodate it to the height of the stack.
11. In a sheet feeding device for printing presses and the like, a flexible moving belt overhanging a stack of sheets, sheet gripping means on the belt to engage the sheets and move them one at a time off the stack, a separating member comprising a friction pad positioned with its friction surface bearing upwardly against the underside of the sheets fed by said belt, said flexible belt flexing readily so as to force the sheets against said friction surface.
12. In a sheet feeding device for printing presses and the like, a flexible moving belt overhanging a stack of sheets, friction means on the

belt to engage the sheets and move them one at a time off the stack, a separating member comprising a rotatable friction pad positioned with its friction surface bearing against the underside of the sheets fed by said belt, whereby the movement of each sheet tends to rotate said separator, said flexible belt flexing readily so as to force the sheets against said friction surface, and spring means to resist said rotation of the separating member.

13. In a sheet feeding device for printing presses and the like, a moving belt overhanging a stack of sheets, sheet gripping means on the belt to engage the sheets and move them one at a time off the stack, a separating member comprising a rotatable friction pad having a rounded friction surface positioned to bear upwardly against the underside of the sheets fed by said belt, whereby the movement of each sheet tends to rotate said separator, said flexible belt flexing readily so as to force the sheets against said friction surface, and spring means to resist rotation of the separating member.

14. In a sheet feeding mechanism for printing presses and the like, a moving belt overhanging a stack of sheets by gravity, sheet gripping means on the belt for removing the sheets one at a time from the stack, a flat plate along which the sheets are moved to be delivered, a pulley at the delivery end of the belt mounted above the plate a sufficient distance for the gripping means on the belt to clear a sheet beneath it, a resilient plate beneath the pulley to raise a sheet for engagement with the gripping means, and means to vary the point of disengagement of a sheet on the resilient plate with the gripping means.

15. In a sheet feeding mechanism for a printing press and the like, a flexible belt adapted to bear on a stack of sheets by gravity, sheet gripping means on the belt to engage the sheets and move them one at a time from the stack, a plate along which the sheets are delivered, a pulley for the belt at the delivery end thereof mounted above the plate a sufficient distance for the gripping means to clear a sheet beneath it, and adjustable means beneath the belt to raise a sheet for engagement with the gripping means.

16. In a sheet feeding device for printing presses and the like, an inclined rack for a stack of sheets, an endless belt, friction pads on the belt to engage the sheets and move them one at a time off the stack, a guide pulley for the belt, means supporting the pulley whereby the belt rests by gravity in juxtaposed relation to the top sheet of said stack, means adapted to separate the main portion of the belt from the top sheet of said stack and thereby permit the friction pads to properly engage the stack, and a separating member disposed beneath the belt and to which the belt conforms.

17. In a sheet feeding mechanism for printing presses and the like, a flexible belt adapted to bear on a stack of sheets by gravity, friction means on the belt to engage the sheets and move them one at a time from the stack, a plate along which the sheets are delivered, a pulley for the belt at the delivery end thereof mounted above the plate a sufficient distance for the friction means to clear a sheet beneath it, adjustable means beneath the belt to raise a sheet for engagement with the friction means, and means to adjust laterally the position of the pulley.

18. In a sheet feeding mechanism for printing presses and the like, a rack for the sheets, a moving belt overhanging the longitudinal center of

the rack and the press and adapted to engage the sheets and move them one at a time from the stack, a series of lateral guide means for the sheets on the rack and extending along the press, 5 said lateral guide means being equally spaced from the longitudinal center of said press and said rack, and means to adjust all the guide means laterally simultaneously relatively to the longitudinal center of said press whereby to accommodate sheets of different width.

10. 19. In a sheet feeding mechanism for printing presses and the like, a rack for a stack of sheets, sheet feeding means to engage the sheets and move them one at a time from the stack and 15 through said press, lateral guide means for the sheets on the rack and extending throughout the press, and means to adjust all of the guide means simultaneously.

20. 20. In a sheet feeding mechanism for printing presses and the like, a moving belt overhanging a stack of sheets by gravity, friction means at intervals on the belt for removing the sheets one at a time from the stack, a flat plate along which the sheets are moved to be delivered, a pulley 25 at the delivery end of the belt mounted above the plate a sufficient distance for the friction means on the belt to clear a sheet beneath it, a resilient plate beneath the pulley to raise a sheet for engagement with the friction means, means to vary 30 the point of engagement of a sheet on the resilient plate with the friction means, the belt being so disposed that there is a brushing contact with the sheet after the friction means have left the sheet, and stop means for arresting movement of the sheet beyond the end of the belt, said stop means being so disposed that the brushing contact between the sheet and the belt holds the sheet thereagainst.

21. In a sheet feeding mechanism for printing 40 presses and the like, a moving belt overhanging a stack of sheets by gravity, friction means at intervals on the belt for removing the sheets one at a time from the stack, a flat plate along which the sheets are moved to be delivered, a pulley at the delivery end of the belt mounted above the plate a sufficient distance for the friction means on the belt to clear a sheet beneath it, a resilient plate beneath the pulley to raise a sheet for engagement with the friction means, means to vary 45 the point of engagement of a sheet on the resilient plate with the friction means, the belt being so disposed that there is a brushing contact with the sheet after the friction means have left the sheet, stop means for arresting movement 50 of the sheet beyond the end of the belt, said stop means being so disposed that the brushing contact between the sheet and the belt holds the sheet thereagainst, a pivoted guide member beyond the delivery end of the belt under which 55 the sheet travels and which bears downwardly on the sheet by gravity, and means carried by the guide member to resist reverse movement of the sheet.

22. A sheet feeding mechanism for printing 60 presses and the like comprising a moving belt, means guiding said belt so that a portion thereof

between said guide means rests by gravity in juxtaposed relation to a pile of sheets to be fed, sheet gripping means on a portion of said belt for contacting and feeding the topmost sheet of said pile, said belt moving against gravity as said gripping means contact said sheets whereby to allow said gripping means to move against said sheets. 5

23. A sheet feeding mechanism for printing 10 presses and the like comprising a moving belt, means guiding said belt so that a portion thereof between said guide means rests by gravity in juxtaposed relation to a pile of sheets to be fed, and sheet gripping means on a portion of said belt for contacting and feeding the topmost sheet 15 of said pile.

24. A sheet feeding mechanism for printing 20 presses and the like comprising a moving belt, means guiding said belt so that a portion thereof between said guide means rests by gravity in juxtaposed relation to a pile of sheets to be fed, sheet gripping means on a portion of said belt for contacting and feeding the topmost sheet of said pile, said belt and its guide means moving against gravity as said gripping means contact 25 said paper whereby to allow for the engagement of said gripping means with said topmost sheet.

25. In a sheet feeding device for printing 30 presses and the like embodying means for holding a stack of sheets, means to engage the sheets and move them one at a time off the stack, a separating member comprising a rotatable friction pad positioned with its friction surface bearing against the underside of the sheets fed by said sheet engaging means, whereby the movement of 35 each sheet relatively to said separating member tends to rotate said separating member, and spring means to resist rotation of the separating member.

26. In a sheet feeding mechanism for a printing 40 machine of the class in which sheets of paper are fed successively through the machine relatively to type and then out of the machine, sheet feeding means to engage the sheets and move them through the machine, a series of guides for 45 the opposite side edges of the sheets maintaining said sheets in proper alignment in their passage through the machine, and means for simultaneously moving the guides for the opposite edges of said sheets toward and away from one another 50 to accommodate sheets of varying width.

27. In a sheet feeding mechanism for a printing 55 machine of the class in which sheets of paper are fed successively through the machine relatively to type and then out of the machine, sheet feeding means to engage the sheets and move them through the machine, a series of guides for the opposite side edges of the sheets maintaining 60 said sheets in proper alignment in their passage through the machine, gearing connecting the said guides, and means for rotating the said gearing whereby to move the guides for the opposite edges of said sheets toward and away from one another to accommodate sheets of varying width. 65

JOHN DUKE TYLER.
